UNITED STATES PATENT OFFICE.

MARY A. OLIVER, OF OSWEGO, NEW YORK.

DESIGN FOR A BOTTLE.

SPECIFICATION forming part of Design No. 21,279, dated January 5, 1892.

Application filed September 18, 1891. Serial No. 406,161. Term of patent 3½ years.

To all whom it may concern:

Be it known that I, MARY A. OLIVER, a citizen of the United States, residing at Oswego, in the county of Oswego and State of New York, have invented and produced a new and original Design for a Bottle, of which the following is a specification, reference being had to the accompanying drawing, forming a part thereof.

10 The drawing represents a bottle in side elevation shaped in accordance with my design. The main feature of the design consists in a kettle-like figure having knobs or balls on its bottom and a neck at its top surmounted by a disk D, the periphery of which projects

15 beyond the upper edge of the neck.

A is the body of the bottle, in general contour resembling a kettle.

B represents ball or knob like figures on the under side of the bottle.

20 C is a tapering neck on the top of the body and surmounted by a disk D, the periphery of which projects beyond the upper edge of the neck.

25 I claim—
The design for a bottle, substantially as described and shown.

MARY A. OLIVER.
